TIME STAMP

Louis Melind, Chicago, Ill.

Application June 25, 1934, Serial No. 732,221

16 Claims. (Cl. 101—373)

This invention relates to stamps, and is more particularly concerned with stamps of the type having a stamping face and a pointer or other indicating element associated therewith, the indicating element being adjustable with respect to the stamping face in order that it may be moved to point to any one of a number of indications carried by said face.

One of the objects of the invention resides in the provision of means of simple construction for readily adjusting the indicating element with respect to the stamping face.

Another object of the invention resides in the provision of a stamp of the character described having the stamping face, together with its adjustable indicating element, affixed to the lower face of the stamp, an indicating dial having indications thereon corresponding to the indications on the stamping face, affixed to the upper face 20 of the stamp, and means of simple construction connecting the indicating dial with the adjustable element of the stamping face, whereby the user may be guided by the upper dial for moving the adjustable indicating element to any desired indication on the stamping face, and without the necessity of turning the stamp over to observe the stamping face during such adjustment of the indicating element.

A further object of the invention resides in locating the upper indicating dial on the stamp in such position that the stamp can readily be held in the hands and adjusted to give any indication desired, and without the hands of the operator in any way obscuring such dial during the adjusting process.

A still further object of the invention resides in the provision of simple and positive means for connecting the upper indicating dial with the adjustable element of the stamping face for joint operation.

Further objects and advantages of the invention will appear from the following detailed description when taken in connection with the accompanying drawing, in which:

Figure 1 is a vertical sectional view through a stamp embodying the principles of the present invention;

Figure 2 is a bottom plan view of the stamp of Figure 1, showing the bottom stamping face and its adjustable indicating element; and

Figure 3 is a top plan view of the stamp of Figure 1, showing the upper indicating dial.

I have shown my invention as embodied in a stamp of the type commonly employed for stamping the time of reception or transmission of let-

ters, papers, and the like. It is to be understood, however, that I do not intend to limit the stamp of my invention to such use alone, as it is capable of many other uses which will readily appear to those skilled in the art.

5

The stamp comprises an upper section 4 and a lower section 5, each of which is preferably so shaped that when section 4 is superposed upon section 5, as shown in Figure 1 of the drawing, they will form a stamp of convenient shape to fit 10 the hand of the user. These sections are preferably formed of wood, although they may be formed of any other suitable material. Sections 4 and 5 are both mounted upon a sleeve 6, with section 4, which comprises the handle of the 15 stamp, being mounted upon the sleeve for relative turning movement with respect to section 5. The sleeve 6, which may be formed of any suitable metal, extends entirely through a central longitudinal bore 7 in section 4 and projects 20 into a central longitudinal bore 8 formed in section 5. Bore 8 forms a continuation of the bore 7 and, at its lower end, is reduced in diameter to form an annular shoulder 9, which provides a seat for the lower end of sleeve 6. Sleeve 6 is 25 anchored in bore 8 of section 5 so that section 5 will be held rigid with respect to the sleeve, while the sleeve has a relatively loose fit in bore 7 of section 4, so that section 4 may readily rotate thereon, and with respect to section 5 of 30 the stamp. Preferably, a washer 11 is disposed about the sleeve 6 and between sections 4 and 5 of the stamp to provide a bearing for the two sections of the stamp. This washer may be of brass or any other suitable material.

35

On its top face 12, section 4 of the stamp is provided with a recess 13 for the reception of an indicating dial 14. This dial, which may be formed of brass or any other suitable material, embraces the sleeve 6 and is rigidly secured 40 thereto at 15, in any suitable or preferred manner. Inasmuch as sleeve 6 is held rigid with section 5 of the stamp, the indicating dial 14 will, therefore, also be held rigid with section 5. A second recess 16, of slightly larger diameter 45 than recess 13, is also formed in top face 12 of section 4, and is adapted for the reception of two discs, indicated at 17 and 18, respectively. Disc 17 seats on an annular shoulder 19 formed by recess 16, and disc 18 is superposed and seats 50 upon disc 17. Both of these discs are rigidly secured to section 4 of the stamp as by means of nails 20, or in any other suitable or preferred manner. Disc 17 is preferably formed of transparent material, such as celluloid, while disc 18 55

is preferably formed of metal, such as brass or the like. Disc 18 is provided with an opening forming an observation window 21, adjacent the periphery thereof, through which the indications 5 22 on the indicating dial 14 may be viewed. Adjacent the window 21 the disc has an arrow 23 stamped therein, the purpose of which will hereinafter be explained. A slot 24, formed in disc 18, substantially centrally thereof, is adapted to 10 snugly receive the reduced end 25 of a shaft 26. This shaft 26 is rotatably mounted in the sleeve 6 and, inasmuch as disc 18 is held rigid with respect to section 4 of the stamp, such disc, by reason of the reduced end of the shaft extending 15 into the slot in said disc, will key shaft 26 to section 4 of the stamp for rotation therewith.

Shaft 26 extends entirely through sleeve 6 and reduced portion 10 of bore 8, and projects for a short distance into a recess 27 formed in the 20 underface 28 of section 5 of the stamp. This recess is adapted to receive the printing stamp and its associated indicating element.

The indicating element comprises an inverted annular cup member 29, formed of brass or any 25 other suitable material. This cup member is disposed in recess 27 and abuts the lower end of shaft 26, to which it is rigidly secured for rotation therewith, by means of a screw 30. Screw 30 extends through the cup member, substantially centrally thereof, and threads into a threaded bore 31 in shaft 26. A pad 32 seats in cup member 29 and is secured to part 33 and flange 34 thereof as by means of a suitable adhesive. If desired, pad 32 may be secured in cup 35 member 29 in any other suitable or preferred manner.

Pad 32 is preferably formed of rubber, although any other suitable resilient material may be employed, and is of such thickness that it will 40 extend for a short distance below the lower face 28 of section 5 of the stamp. The outer face 35 of disc 32 has a block 36 projecting therefrom. Block 36 is preferably formed of rubber, or any other suitable resilient material, and carries an 45 arrow 37 and the word "Received". This arrow 37 is aligned with the arrow 23 stamped in the indicating disc 18 on the upper face of section 4 of the stamp. The outer face 35 of disc 32 is provided with an annular shoulder, as indicated 50 at 38, and this shoulder 38 contacts the inner face 39 of an inturned flange 40 formed on a dial ring 41. Dial ring 41 is also preferably formed of rubber, or any other suitable resilient material, and the outer face 42 of the flange 40 carries 55 time indications which correspond with the time indications formed on dial plate 14. The dial ring extends upwardly into recess 27 in section 5 and has its lower face 42 terminating in substantially the plane of the arrow 37. The 60 side walls 43 of the dial ring 41 have a relatively close fit with the side walls of the recess 27 and are secured thereto by a suitable adhesive, or by any other suitable or preferred means. At its upper face 44, the dial ring 41 contacts one 65 side of a disc 45, which may be formed of brass or any other suitable material. The opposite face of disc 45 has a pad 46, of rubber or other suitable resilient material, secured thereto, this pad contacting the face 47 of recess 27, to which 70 it may be secured or not, as desired. The disc 45 and pad 46 form a cushioning element for dial ring 41.

From the foregoing it will be noted that indicating dial 14 and dial ring 41, which carry corresponding indications, are fixed with respect to

each other. Likewise, the indicator arrow 23, associated with indicating dial 14, and the indicating arrow 37, associated with the dial ring 41, are connected together for turning movement with respect to the indicating dial and the dial ring. It will be apparent, therefore, that upon rotation of section 4 of the stamp, shaft 26, which is keyed to section 4 as hereinbefore explained, will rotate disc 32, which is rigidly secured thereto. As the arrow on disc 32 is 10 aligned with the arrow on disc 18, all that is necessary to adjust the stamp is to rotate section 4 until one of the indications on dial 14 is opposite the arrow 23 on disc 18, whereupon the arrow on disc 32, which will be rotated upon 15 rotation of section 4, will point to the corresponding indication on dial ring 41. It will be observed, therefore, that the adjustable arrow on the lower dial may be adjusted without the necessity of turning the stamp over during the 20 adjusting process. Likewise, as the indicating dial is located in the upper face of the stamp, the stamp may be readily grasped by both hands during adjustment thereof, without in any way obscuring the indicating dial. 25

While a preferred embodiment of the invention has been illustrated and described, by way of example, it will be obvious that changes may be made therein within the spirit and scope of the invention and, therefore, the invention is not to 30 be limited to the form herein disclosed, except insofar as it may be so limited in the appended claims.

I claim:

1. A stamp of the class described comprising a 35 body portion, a handle secured to said body portion and rotatable with respect thereto, said handle having a recess formed in the upper face thereof, a stamping dial disposed in said body portion, an indicating dial disposed in the recess 40 in said handle, said dials being fixed with respect to each other, a movable indicating element associated with said stamping dial, and an indicator associated with said indicating dial, and means connecting said indicators together for joint ro- 45 tation with respect to said dials.

2. A stamp of the class described comprising a lower section, an upper section superposed on said lower section, a stamping dial disposed in said lower section, an indicating dial disposed in said 50 upper section, means mounting said sections for relative turning movement with respect to each other and holding said dials fixed with respect to each other, an indicating element associated with said stamping dial and an indicator associated with said indicating dial, and means connecting said indicators together for joint rotation with respect to said dials. 55

3. A stamp of the class described comprising a lower section, an upper section having a recess in 60 the upper face thereof superposed on said lower section, a stamping dial disposed in said lower section, an indicating dial disposed in the recess in said upper section, means mounting said sections for relative turning movement with respect to each other and holding said dials fixed with 65 respect to each other, an indicating element associated with said stamping dial and an indicator associated with said indicating dial, and means connecting said indicators together for joint ro- 70 tation with respect to said dials.

4. A stamp of the class described comprising a lower section, an upper section superposed on said lower section, a stamping dial disposed in said lower section, an indicating dial disposed in said 75

upper section, means comprising a sleeve mounting said sections for relative turning movement with respect to each other and holding said dials fixed with respect to each other, an indicating element associated with said stamping dial and an indicator associated with said indicating dial, and means connecting said indicators together for joint rotation with respect to said dials.

5. A stamp of the class described comprising a lower section, an upper section superposed on said lower section, each of said sections having a longitudinally extending bore formed therein, a stamping dial disposed on said lower section, an indicating dial disposed in said upper section, means comprising a sleeve disposed in the bore in said sections for mounting said sections for relative turning movement with respect to each other and holding said dials fixed with respect to each other, an indicating element associated with said stamping dial and an indicator associated with said indicating dial, and means connecting said indicators together for joint rotation with respect to said dials.

6. A stamp of the class described comprising a lower section, an upper section superposed on said lower section, each of said sections having a longitudinally extending bore formed therein, a sleeve disposed in said bore, said sleeve having a loose fit in said upper section and being rigidly secured to said lower section, a stamping dial disposed on said lower section, an indicating dial disposed in said upper section and secured to said sleeve, said sleeve and said lower section holding said dials fixed with respect to each other, an indicating element associated with said stamping dial and an indicator associated with said indicating dial, and means connecting said indicators together for joint rotation with respect to said dials.

7. A stamp of the class described comprising a lower section, an upper section having a plurality of recesses formed in the upper face thereof superposed on said lower section, a stamping dial disposed on said lower section, an indicating dial disposed in one of the recesses in said upper section, means mounting said sections for relative turning movement and holding said dials fixed with respect to each other, an indicating element associated with said stamping dial, a disc disposed in another of said recesses in said upper section and having an indicator formed thereon for cooperating with said indicating dial, and means connecting said disc and said indicating element together for joint rotation with respect to said dials.

8. A stamp of the class described comprising a lower section, an upper section having a plurality of recesses formed in the upper face thereof superposed on said lower section, a stamping dial disposed on said lower section, an indicating dial disposed in one of the recesses in said upper section, means mounting said sections for relative turning movement and holding said dials fixed with respect to each other, an indicating element associated with said stamping dial, a disc having a slot formed therein disposed in another of said recesses in said upper section and having an indicator formed thereon for cooperating with said indicating dial, and means engaging in said slot in said disc and connected with said indicating element to secure said disc to said indicating element for joint rotation with respect to said dials.

9. A stamp of the class described comprising a lower section, an upper section superposed on said lower section, each of said sections having a longitudinally extending bore formed therein, a stamp-

ing dial disposed on said lower section, an indicating dial disposed in said upper section, means comprising a sleeve disposed in the bore in said sections for mounting said sections for relative turning movement with respect to each other and holding said dials fixed with respect to each other, an indicating element associated with said stamping dial, a disc having an indicator formed thereon associated with said indicating dial, and means rotatably mounted in said sleeve and connecting said disc and said indicating element together for joint rotation with respect to said dials.

10. A stamp of the class described comprising a lower section, an upper section superposed on said lower section, each of said sections having a longitudinally extending bore formed therein, a stamping dial disposed on said lower section, an indicating dial disposed in said upper section, means comprising a sleeve disposed in the bore in said sections for mounting said sections for relative turning movement with respect to each other and holding said dials fixed with respect to each other, an indicating element associated with said stamping dial, a disc having a slot formed therein associated with said indicating dial, said disc having an indicator formed therein for cooperation with said indicating dial, and a shaft rotatably mounted in said sleeve, said shaft engaging in the slot in said disc and connecting said disc to said indicating element for joint rotation therewith and with respect to said dials.

11. A stamp of the class described comprising a lower section, an upper section having a plurality of recesses formed in the upper face thereof superposed on said lower section, each of said sections having a longitudinally extending bore formed therein, a stamping dial disposed on said lower section, an indicating dial disposed in one of the recesses in said upper section, means comprising a sleeve disposed in the bore in said sections for mounting said sections for relative turning movement with respect to each other and holding said dials fixed with respect to each other, an indicating element associated with said stamping dial, a disc having a slot formed therein disposed in another one of said recesses in said upper section, said disc having an indicator formed thereon for cooperation with said indicating dial, and a shaft rotatably mounted in said sleeve, said shaft engaging in the slot in said disc and connecting said disc to said indicating element for joint rotation therewith and with respect to said dials.

12. A stamp of the class described comprising a lower section, an upper section having a plurality of recesses formed in the upper face thereof superposed on said lower section, each of said sections having a longitudinally extending bore formed therein, a stamping dial disposed on said lower section, an indicating dial disposed in one of the recesses in said upper section, means comprising a sleeve disposed in the bore in said sections for mounting said sections for relative turning movement with respect to each other and holding said dials fixed with respect to each other, an indicating element associated with said stamping dial, a disc having a slot formed therein disposed in another of said recesses in said upper section, said disc having an indicator formed thereon for cooperation with said indicating dial, means rigidly securing said disc to said upper section for rotation therewith, and a shaft rotatably mounted in said sleeve, said shaft engaging in the slot in said disc and connecting said disc with said indicating element, whereby upon turn-

ing movement of said upper section said indicators will be rotated with respect to said dials.

13. A stamp of the class described comprising a lower section, an upper section having a plurality of recesses formed in the upper face thereof superposed on said lower section, each of said sections having a longitudinally extending bore formed therein, a sleeve disposed in the bore in said sections, said sleeve having a loose fit in said upper section and being rigidly secured to said lower section, an indicating dial disposed in one of the recesses in said upper section and fixed to said sleeve, a disc having a slot formed therein disposed in another of said recesses and above 10 said indicating dial, said disc having an observation window therein for viewing said dial and having an indicator cooperating with the dial, means rigidly securing said disc to said upper section, a shaft rotatably mounted in said sleeve 15 and having a reduced end engaging in the slot in said disc, said shaft extending into a recess formed in the lower face of said lower section, a dial ring disposed in the recess in said lower section, a cup member disposed within said dial ring 20 and secured to said shaft, and an indicating member secured to said cup member for cooperation with said dial ring, whereby upon rotation of said upper section said disc and indicating member will be jointly rotated with respect to 25 said dials.

14. A stamp of the class described comprising a lower section, an upper section having a plurality of recesses formed in the upper face thereof superposed on said lower section, each of said sections having a longitudinally extending bore formed therein, a sleeve disposed in the bore in said sections, said sleeve having a loose fit in said upper section and being rigidly secured to said lower section, an indicating dial disposed in one of the recesses in said upper section and fixed to said sleeve, a disc having a slot formed therein disposed in another of said recesses and 30

above said indicating dial, said disc having an observation window therein for viewing said dial and having an indicator cooperating with the dial, means rigidly securing said disc to said upper section, a shaft rotatably mounted in said sleeve and having a reduced end engaging in the slot in said disc, said shaft extending into a recess formed in the lower face of said lower section, a dial ring disposed in the recess in said lower section, a cushioning element disposed in said recess between the upper face thereof and said dial ring, a cup member disposed within said dial ring and secured to said shaft, a cushioning element secured to said cup member, and an indicating member carried by said cushioning element for cooperation with said dial ring, whereby upon rotation of said upper section said disc and said indicating member will be jointly rotated with respect to said dials. 10

15. A stamp of the class described comprising a lower section and an upper section rotatably mounted on said lower section, an indicating dial disposed in the upper face of said upper section, and a stamping dial carried by said lower section, indicator means associated with each of said 20 dials, and means connecting said indicators together for joint rotation with respect to said dials. 25

16. A stamp of the class described comprising a body portion and a handle therefor, a stamping dial and a cooperating indicating dial fixed with respect to each other and associated with said body and handle portion, indicating elements associated with each of said dials, means connecting 30 said indicating elements together for joint movement with respect to said dials, and means locating said indicating dial with respect to said stamp whereby the body portion and handle of the stamp will be disposed substantially entirely below said 35 dial. 40

LOUIS MELIND.
